TEAR-DROP-SHAPED BICYCLE LANTERN

Eric T. New, Kew Gardens, N. Y.

Application March 26, 1957, Serial No. 45,443

Term of patent 7 years

(Cl. D48—24)

Fig. 1.

Fig. 2.

Fig. 3.

Fig. 4.

Fig. 1 is a top plan view of a tear-drop-shaped bicycle lantern showing my new design;

Fig. 2 is a side elevational view thereof;

Fig. 3 is a bottom plan view thereof; and

Fig. 4 is a front elevational view thereof.

I claim:

The ornamental design for a tear-drop-shaped bicycle lantern, substantially as shown.
